UNITED STATES PATENT OFFICE.

JOHN CURRIN, OF SOUTHBRIDGE, MASSACHUSETTS, ASSIGNOR TO SYLVESTER EASTMAN, OF PROVIDENCE, RHODE ISLAND.

EYEGLASSES.

SPECIFICATION forming part of Letters Patent No. 425,595, dated April 15, 1890.

Application filed July 24, 1889. Serial No. 318,530. (No model.)

To all whom it may concern:

Be it known that I, JOHN CURRIN, a citizen of the United States, and a resident of Southbridge, in the county of Worcester and State 5 of Massachusetts, have invented a new and useful Improvement in Eyeglasses, set forth in the annexed specification, which contains a full, clear, and exact description of my invention, accompanied by drawings, forming 10 a part of the same, and showing an eyeglass embodying the essential features of my invention, and in which—

Figure 1 represents a front view of the eyeglass. Fig. 2 is a top view. Fig. 3 is a top 15 view with the nose-guard springs removed. Fig. 4 represents an elevation of an eyeglass, showing a modified form of nose-guard spring. Fig. 5 is a sectional view of one of the nose-guards on line X X, Fig. 6. Fig. 6 20 represents a rear view of one of the nose-guards with the nose-guard spring removed; and Fig. 7 is a transverse sectional view of one of the nose-guards on line Y Y, Fig. 6.

Similar letters refer to similar parts in the 25 several views.

My invention relates to that class of eyeglasses which are attached to the nose by means of nose-guards connected with the frame of the eyeglass by springs whose tension serves to press the nose-guards against the sides of the nose.

In the accompanying drawings, A A denote the eye-wires; B B, the lenses.

C C are lugs projecting inwardly from the 35 eye-wires A A.

D denotes the bow-spring.

E are the nose-guards attached to the free 40 ends of the nose-guard springs F F. The fixed ends of the nose-guard springs are attached to the lugs C C, and each of the springs is carried from the lug to which it is attached over the bow-spring D, and parallel with it to the central portion of the bow-spring. The nose-guard spring is then returned at G parallel with the bow-spring, and 45 having its free end H turned upwardly, and entering a mortise I in the metallic band J of the nose-guard E. The nose-guards are formed of the metallic strips J, having their

longest sides turned over at K to partially 50 inclose and hold the strips of cork, rubber, or other material suitable to rest against the sides of the nose. The free ends of the nose-guard springs F F enter the mortises I I and are attached to the inner sides of the metallic strips J J.

As shown in Fig. 1 of the drawings, the nose-guard springs are returned upon themselves, forming a curved loop, as at L; but, if desired, the nose-guard spring can be made 60 of two separate pieces in each spring, with the pieces fastened together at a a by screws, rivets, or soldering.

The construction of that part of the eyeglass comprising the eye-wires, lenses, and 65 bow-spring is substantially the same as the eyeglasses now in common use; but I attach the nose-guards to separate and independent springs, allowing the glasses to be placed upon the nose without bringing any strain 70 upon the bow-spring and consequent displacement of the lenses.

I do not herein claim the use of an independent spring to which the nose-guards are attached to be broadly new; but in the peculiar form of the nose-guard spring shown I am able to connect the nose-guard springs with the lugs to which the bow-spring is attached, bringing the strain of both bow-spring and nose-guard springs upon the same 80 point of the frame, which can be made sufficiently heavy and strong at that point for the purpose; and I also secure a long section of the nose-guard spring to act upon the nose-guards, the entire portion from the nose-guards to the looped section L receiving the strain as the nose-guards are separated in placing the eyeglasses upon the nose. The sides K of the strips J are bent over to partially inclose and enter the sides of the strip 90 M, which is preferably made of cork or a similar semi-elastic substance, and the sides K form acute angles with the strip M, which is compressed between the edges of the sides K K, forming a dovetailed joint, as shown in 95 Fig. 7 of the drawings.

What I claim as my invention, and desire to secure by Letters Patent, is—

The combination, with the eye-wires of a pair of eyeglasses, of nose-guard springs attached at one of their ends to the eye-wires and carrying at their free ends nose-guards, said nose-guard springs extending from the eye-wires over the bow-spring and returning in substantially parallel lines to their point of attachment to said eye-wires, and then being curved downward and inward, substantially as described.

JOHN CURRIN.
